UNITED STATES PATENT OFFICE.

WILLIAM R. McDONALD AND WILLIAM J. MILNE, OF PORTLAND, OREGON.

DISPENSING APPARATUS.

1,219,651.

Specification of Letters Patent. Patented Mar. 20, 1917.

Application filed March 12, 1915. Serial No. 13,975.

To all whom it may concern:

Be it known that we, WILLIAM R. McDONALD and WILLIAM J. MILNE, citizens of the United States, residing at Portland, in the county of Multnomah and State of Oregon, have invented certain new and useful Improvements in Dispensing Apparatus, of which the following is a specification.

This invention contemplates an improved 10 apparatus especially designed for use in dispensing malted milk, or similar powdered or granular substances, and has as its primary object to provide a device of this character adapted to be employed in drug stores or in 15 like situations.

The invention has as a further object to provide a device of this character adapted to deliver from the bulk a predetermined quantity of material and wherein means will be 20 provided for adjusting or regulating the quantity of material to be delivered upon each actuation of the delivering mechanism.

A further object of the invention and of equal importance with the foregoing, is to 25 provide a device of this character which will be neat and attractive in appearance, and which, in use, will furnish a thoroughly sanitary article.

A still further object of the invention is to 30 provide a device of this character having a detachably mounted receptacle adapted to contain the quantity of material to be dispensed, and wherein the said receptacle may be readily removed and also wherein the 35 other parts of the device may be readily disconnected from each other to easily permit of cleaning should necessity arise.

Other and incidental objects will appear 40 as the description proceeds and in the drawings wherein we have illustrated the preferred embodiment of our invention and wherein similar reference characters designate corresponding parts throughout the several views,

45 Figure 1 is a perspective view of our improved device mounted upon a stand,

Fig. 2 is a horizontal sectional view taken 50 through the casing of the valve body and showing the valve body in normal position therein, with the cap plate removed,

Fig. 3 is a fragmentary vertical sectional view particularly showing the mounting of the valve body,

Fig. 4 is a fragmentary perspective view

showing the mounting of the partition defining the valve pocket,

Fig. 5 is a detail perspective view of the valve body detached,

Fig. 6 is a fragmentary sectional view on the line 6—6 of Fig. 2,

Fig. 7 is a fragmentary perspective view showing the filling opening formed in the cap plate of the device, and

Fig. 8 is a fragmentary sectional view.

In carrying out our invention, we employ 65 a substantially cylindrical casing 10 which is closed at one end by a bottom wall 11 having a discharge opening 13 formed therein at its periphery and upon one side of the casing. As best shown in Fig. 2 of the drawing, the opening 13 is preferably defined by opposite radially extending side edges and concentric arcuate end edges. Depending 70 from the bottom wall 11 and surrounding the discharge opening 13 is a spout 14.

75 Removably fitting in the casing 10 and mounted to rotate therein, is a valve body designated as a whole by the reference numeral 15. This valve body includes a preferably cylindrical hub 16 open at its ends, 80 and upon which is mounted at one side and in spaced relation thereto, an arcuate plate 17 adapted to fit against the vertical wall of the casing 10 as best shown in Fig. 3 of the drawings. The plate 17 is arranged in concentric relation to the hub 16 and at its extremities is bent laterally and terminally secured to the hub in any suitable manner as shown at 18.

The plate 17 is of equal height with the 90 hub 16 and extending between the hub and the said plate is a partition wall 19 best shown in dotted lines in Fig. 2 of the drawings, the terminals of said wall being bent laterally and respectively secured to the hub 95 and the plate in any suitable manner. Mounted upon the upper edges of the plate 17 and of the hub 16, at one end of the plate is a closure plate 20 having radially extending sides, the outer edge of said plate being 100 struck on the arc of a circle and terminating flush with the outer face of the plate 17.

Formed on the upper edges of the hub 16 and the plate 17 upon one side of the plate 20 are series of spaced alined notches 21. Removably fitted between the hub 16 and the plate 17 is a partition 22, the said partition being provided at one extremity thereof,

with laterally projecting lugs 23 adapted to removably engage in corresponding notches of the said series of notches 21. The partition 22 is of a width equal to the width of 5 the hub and the plate 17, and, as will be observed, is thus adapted to coact with the partition 19 in defining a pocket, the partition 22 being adjustable through the medium of the series of notches 21 either toward or 10 away from the partition 19, to vary the capacity of the pocket.

Formed in the hub 16 upon one side thereof is a slot 24 and mounted within the hub opposite said slot is an arcuate strip 25 of 15 less radius than the hub and is secured thereto at its extremities in any suitable manner. Formed in the strip 25 in alinement with the slot 24 is a slot 26.

The vertical wall of the casing 10 upon 20 one side thereof is provided with an arcuate slot 27, of substantially 90° in length and removably fitted in said slot to extend freely through the slot 24 of the hub 16, is the shank 28 of a handle 29, the said handle adjacent its outer extremity being preferably offset as best shown in Fig. 3 of the drawings. Formed on the inner extremity of the shank 28 is a terminal lug 30 adapted to 25 removably engage within the notch 26 of the strip 25. It will be seen from the preceding description that the valve body 15 may be readily removed from the casing by detaching the handle 29.

Mounted axially of the casing is a rock 30 shaft 31, one terminal of which is screw threaded and extends freely through a suitable bore formed in the bottom wall 11 of the casing and detachably receives a nut 32 which connects the shaft with the casing. 35 Formed on the shaft 31 at the adjacent extremity thereof, is a squared enlargement or head 33 which removably fits within a suitable opening formed in the shank 28 of the handle 29. Consequently, when the handle 40 is operated to turn the valve body 15, rotary movement will be correspondingly imparted to the shaft 31.

Freely surrounding the head 33 of the shaft and bearing between the shank 28 of 45 the handle and the bottom wall 11 of the casing is a helical spring 34 which, at one extremity, is provided with a laterally disposed terminal lug 35 detachably engaging within a suitable opening formed in the bottom wall 11 of the casing. The opposite extremity of the spring is extended radially and is arranged to detachably engage within a suitable opening formed in the hub 16. The spring 34 is adapted to maintain the 50 valve body 15 in the normal position shown in Fig. 2 of the drawings, with the pocket of the valve body disposed upon one side of the discharge opening 13. It will thus be observed that the rock shaft 31 provides a

pivotal center for the valve body 15 about 65 which the said body is mounted to rotate. The handle 29 is adapted for movement to shift the valve body to position with the pocket thereof defined by the partition wall 19 and 22 disposed over the discharge opening 13, the said handle being operated against the tension of the spring 34. Consequently, when the handle is released, said spring will immediately return the valve body to normal position as shown in Fig. 2 75 of the drawings.

Removably fitted upon the shaft 31 to rest upon the adjacent upper face of the valve body is a cap plate or partition 36 which, 80 upon one side, is provided with a notch 37, and struck from the wall of the casing 10 is a lug 38 freely engaging in said notch. The cap plate 36 will thus, through the medium of the lug 38 be held stationary within the casing.

The cap plate 36 is of a diameter substantially equal to the internal diameter of the casing 10 and upon one side thereof is provided with a filling opening 39 best shown in Fig. 7 of the drawings, the said opening being similar in contour to the discharge opening 13 and being of equal area therewith.

The filling opening 39 is so arranged that, in the normal position of the valve body 15, the said opening will align with the pocket 95 of the said valve body as best shown in Fig. 3 of the drawings. Consequently, when the valve body is moved to normal position, the pocket thereof may be readily filled through the said opening.

The rock shaft 31 is preferably of a length to extend above the casing 10 and, at the adjacent upper terminal thereof, is squared, to detachably receive an agitator 40 preferably provided with quadrantly spaced radial 105 arms to which are secured laterally projecting and upstanding pins 41. The agitator is thus mounted to rotate with the rock shaft while the adjacent extremity of the shaft is screw threaded to detachably receive a nut 42 for holding the agitator in position thereon.

The circumferential wall of the casing 10 is internally screw threaded adjacent the free extremity thereof as shown at 43 and 115 detachably receives the adjacent externally screw threaded extremity of a suitable receptacle 44, it being observed that the agitator 40 is arranged to project within the adjacent lower extremity of the receptacle. Formed on the outer terminal of the receptacle is a reduced neck 45 which provides a filling opening for the receptacle and enclosing the said opening is a screw threaded cap 46. It will be observed that while the receptacle 44 may be readily removed from the casing 10, that in order to introduce a 120 quantity of material within the receptacle, it

will simply be necessary to remove the cap 46, but it will be noted that in thus detachably mounting the receptacle, the said receptacle may be readily disconnected so that it 5 may be easily cleaned.

From the preceding description it is thought that the operation of our improved device will be readily understood. When used in drug stores or other similar places, 10 the device will preferably be supported upon a suitable stand, conventionally shown at 47, in such position that a glass may be readily arranged beneath the funnel 14. However, it will be seen that the device may also be 15 readily mounted upon a wall or other structure.

In use, the receptacle 44 is filled with the material to be dispensed which, in the normal position of the valve body, may readily 20 center the pocket in the said valve body. The handle 29 may then be operated in the manner previously described to move the said pocket to a position over the discharge opening 13 when the material within the pocket 25 will be immediately discharged. In this connection, particular attention is directed to the fact that when the valve body is so moved, the plate 20 of the said valve body will, at the same time, be moved to close the 30 filling opening 39 in the cap plate 36 as shown in detail in Fig. 8 of the drawings, so that the bulk of material within the receptacle 44 will be withheld pending the return of the valve body to normal position. 35 As best shown in detail in Fig. 6 of the drawings, the cap plate 36 is adapted to shut off direct communication between the interior of the receptacle and the discharge opening. In this connection, it is also to be 40 observed that, as previously set forth, the partition 22 may be adjusted to regulate the quantity of material to be discharged upon each actuation of the valve body.

Since the agitator 40 is mounted to rotate 45 with the rock shaft 31, the said agitator will act to stir the bulk of material within the receptacle 44 each time the handle 29 is operated, to thus insure a proper feeding of the material to the valve body.

50 Having thus described our invention, what we claim and desire to secure by Letters Patent is:—

1. A device of the character described including a casing provided with a discharge 55 opening, a valve body arranged within the casing, a partition coöperating with the valve body and provided with a filling opening, yieldable means engaging the partition for holding it against movement with said 60 filling opening arranged out of alinement with the discharge opening, and means for shifting the valve body to selectively coöperate with said openings.

2. A device of the character described in-

cluding a casing provided with a discharge 65 opening, an agitator mounted within the casing, a valve body independent with respect to the agitator and provided with a hollow hub, a partition coöperating with the valve body and provided with a filling opening 70 arranged out of alinement with the discharge opening, and means projecting into the hub and operatively connecting the agitator with the valve body with the said means operable for rotating the valve body to selectively coöperate with said openings and simultaneously rotating the agitator.

3. A device of the character described including a casing provided with a discharge opening, a valve body shiftably mounted in 80 the casing and provided with a hollow hub, a partition coöperating with the valve body and provided with a filling opening arranged out of alinement with the discharge opening, an agitator having a shaft extending 85 through the said hub, there being a slot formed in the wall of the hub, a member mounted within the hub and provided with a slot arranged opposite said first mentioned slot, and a handle engaging in said slots for 90 rotating the valve body to selectively coöperate with said openings and engaging said shaft for connecting the agitator with the valve body to rotate therewith.

4. A device of the character described including a casing provided with a discharge opening, a valve body arranged within the casing and provided with a hollow hub, a partition coöperating with the valve body and provided with a filling opening arranged 95 out of alinement with the discharge opening, an agitator having a shaft extending through said hub, means for rotating the valve body to selectively coöperate with said openings and connecting the shaft with the valve body 100 to rotate therewith, and yieldable means disposed within the hub and engaging the valve body for normally urging the said body to a position closing the said discharge opening.

5. A device of the character described including a casing provided with a discharge opening, a valve body arranged within the casing and provided with a hollow hub, a partition coöperating with the valve body and provided with a filling opening arranged 110 out of alinement with the discharge opening, an agitator having a shaft extending through the hub and free with respect thereto, and a handle projecting into the hub and engaging the said shaft for connecting the agitator 115 with the valve body and operable for rotating the valve body to selectively coöperate with said openings and simultaneously rotating the said agitator.

6. A device of the character described including a casing provided with a discharge opening, a valve body arranged within the casing, said body including spaced members

- having notches formed in the upper edges thereof, a partition between the said members, and a second partition mounted to co-operate with said first mentioned partition
5 to provide a pocket and arranged for selective engagement in corresponding notches for varying the capacity of said pocket, a partition co-operating with the valve body and provided with a filling opening arranged
10 out of alinement with the discharge opening, and means for shifting the valve body to dispose the said pocket to selectively co-operate with the said openings.
7. A device of the character described including a casing provided with a discharge opening, a valve body rotatable within the casing and provided with a hollow hub, a partition co-operating with the valve body and provided with a filling opening arranged
15 out of alinement with the discharge opening, and a handle extending diametrically through the hub at one side thereof and op-

eratively engaged with the hub at its opposite side for shifting the valve body to selectively co-operate with the said openings. 25

8. A device of the character described including a casing provided with a discharge opening, a lug carried by the casing, a valve body rotatable within the casing, a partition co-operating with the valve body and notched to receive said lug for holding the said partition against movement, the said partition being formed with a filling opening arranged out of alinement with the discharge opening, and means for shifting the 30 valve body to selectively co-operate with said openings. 35

In testimony whereof we affix our signatures in presence of two witnesses.
